CROSS-FEED MECHANISM FOR GRINDING MACHINES

Harry Arter, Worcester, and Warren F. Fraser,
Westboro, Mass., assignors to Arter Grinding
Machine Company, Worcester, Mass., a corpora-
tion of Massachusetts

Application December 5, 1946, Serial No. 714,168

17 Claims. (Cl. 51—165)

1

In machines for grinding cylindrical surfaces on articles of work, the relative approaching and receding movements of the grinding wheel and the work piece are usually produced by the operation of a so-called "cross-feed mechanism." Such a mechanism includes a hand wheel which is connected through suitable gearing to the wheel head or the work support so that rotation of said hand wheel relatively adjusts the wheel head and the work support toward or from each other. Usually the hand wheel, or a drum rotatable with it, is graduated to indicate the extent of these approaching and receding movements. Such graduations, however, are difficult to read, and in order to obtain a high degree of accuracy in the work produced, it is necessary to depend more upon micrometer measurements of the work than on the hand wheel graduations.

Additional objections to mechanisms of this type are the fact that they are slow to operate, so that considerable time is required in making large changes in adjustment, and back-lash and torsional strains in the gearing and transmission mechanism also are potential sources of error.

The present invention aims to devise a cross-feed mechanism in which these objectionable features will be eliminated; which will be less laborious and more convenient for the workmen to operate, and in which a high degree of accuracy in the work produced can be easily and quickly achieved.

The nature of the invention will be readily understood from the following description when read in connection with the accompanying drawings, and the novel features will be particularly pointed out in the appended claims.

In the drawings,

Fig. 1 is an end view of a grinding machine embodying features of this invention;

Fig. 2 is a side elevation of parts of the adjusting mechanism provided by this invention, with the motor removed;

Fig. 3 is a vertical, sectional view taken approximately on the line 3—3, Fig. 2;

Fig. 4 is a horizontal, sectional view through the casing of the indicator, the section being taken on the line 4—4, Fig. 5;

Fig. 5 is a vertical, sectional view through the indicator casing, taken on the line 5—5, Fig. 4;

Fig. 6 is a plan view, with some parts in section showing the base on which the wheel head slides;

Fig. 7 is a vertical, sectional view through the wheel head and its supporting devices;

2

Fig. 8 is a vertical, sectional view taken substantially on the line 8—8, Fig. 10, showing a modified form of adjusting mechanism for the wheel head;

Fig. 9 is a sectional view on the line 9—9, Fig. 8;

Fig. 10 is a view, partly in side elevation and partly in section, on the line 10—10, Fig. 8;

Fig. 11 is a partial section of the controlling mechanism for the clutch;

Figs. 12 and 13 are wiring diagrams showing control circuits for the motors which supply power for producing the cross feeding movements of the wheel head;

Fig. 14 is a front elevation of a portion of the switch panel; and

Fig. 15 is a horizontal, sectional view showing those members which support the work for the grinding operation.

Referring first to Fig. 1, the machine there shown is organized on similar lines to that illustrated in Patent No. 1,736,967 issued to one of the present applicants. That is, it comprises a grinding wheel 2 mounted in a wheel head 3 for rapid rotation around its own axis, and such rotation is produced by an electric motor 4 belted to the wheel shaft 5. The work pieces on which the wheel operates are held between work holders, at least one of which work holders is mounted to revolve around the axis of the shaft 6 and is driven as by the motor 7. In the foregoing respects the machine is similar to those common in the grinding machine industry.

In the normal operation of the machine the wheel head and the work holders must have some provision for relative movement toward and from each other, and this is most conveniently accomplished by moving the wheel head rather than the work holders. For this reason the head 3 is mounted on a base 8 which is adjustably bolted to a bed 9, the base being provided with guides 10—10, Figs. 6 and 7, on which the wheel head is slidably mounted. A wear-piece 11 and gib 12—12 cooperate with the guides 10 to support the wheel head in its operative position.

Provision is also made for adjusting the base 8 angularly in a horizontal plane about the pivot 13, Fig. 6, which is fixed in the bed piece 9. For this reason the top of the bed is machined accurately, and the adjusting movement is produced by pivoting a link 14, Figs. 1 and 6, to an arm integral with the base, and extending the threaded end of the link through a bracket 15 which is secured rigidly to a part of the machine

frame or bed. Nuts 16-16 are threaded on this end portion of the link 14 so that by properly manipulating them the angular position of the base 8 may be adjusted at right angles to the axis of the work holders, or in some other desired angular relationship to them. Several bolts 17 extending through arcuate slots in ears, projecting from the margin of the base 8, as best shown in Fig. 6, serve to secure the base in its adjusted position on the bed 9.

In this machine, as in that shown in the patent above mentioned, the grinding wheel 2 is mounted on an eccentric sleeve or quill which is supported in bearings so that by oscillating the quill, the wheel may be moved bodily while the wheel head remains stationary, and this arrangement is employed to move the wheel into engagement with the work; hold it there for the desired length of time; and then to withdraw it while the work piece previously operated upon is moved out of grinding position and another is indexed into position to be ground. And this cycle of operations is repeated on each work piece until some change in the character of these articles of work makes it necessary to change the relationship of the parts in some way. However, in initially adjusting the machine to a new article of work, it is usually necessary to move the wheel head 3 forward or backward in order to position the grinding wheel 2 properly for operation on the new work piece.

Important features of this invention reside in a novel mechanism for producing this adjusting movement, by power, but under close control of the workman. Also, in an indicating mechanism operatively associated with this adjusting means, to give easily read measurements of the movements of the wheel head and its wheel.

For this purpose a screw or screw-threaded shaft 18 is secured at one end in the base 8 as shown, for example, in Figs. 6 and 7, and projects rearwardly for a substantial distance beyond the end of the main body of the base. Threaded on it is a nut 20, Fig. 6, having an extended bearing in a bracket 21, Figs. 1, 2 and 3, which is bolted securely to the rear end of the wheel-head and, to all intents and purposes, except for convenience of manufacture, forms a part of said head. The nut can revolve freely on the stationary screw 18 but is held against axial movement relatively to the wheel-head. Consequently, rotation of this nut will operate on the screw 18 to move the entire wheel-head assembly toward and from the work supporting members.

Such rotation preferably is produced by power as, for example, by the electric motor 22 which is bolted to one side of the bracket 21. In the embodiment of the invention illustrated in Figs. 1, 2 and 3, the motor is of the direct current, reversible, variable speed type, arranged to be controlled entirely from a switch panel at the front of the machine through push buttons, or other easily operable switches, as will later be described.

This motor is connected with the nut 20 by a reduction gearing which, as shown in Figs. 2 and 3, comprises a worm 23 fast on the motor shaft 24 and meshing with a worm wheel 25 fast on another worm shaft 26 on which a worm 27 is rigidly secured or is made integral therewith. The nut 20 has the form of a worm gear, or includes a section which consists of a worm gear, meshing with the worm 27. Consequently, the motor 22, when energized, drives the nut 20 at a speed very

much slower than that of the motor shaft, the ratio of the speed reduction being determined by design. A suitable ratio is in the neighborhood of forty to one, so that one revolution of the worm moves the wheel head .005 inch.

The worm shaft 26 is mounted in antifriction bearings which support it against end thrust, as well as radially, and an important advantage of this speed-reducing arrangement is the fact that it lends itself readily to the dual function of adjusting the wheel head and also of operating an indicator. For this purpose a dial casing having a long tubular stem 28 and a head 30 is secured to the top of the bracket 21 and extends upward therefrom. Mounted in this casing is a vertical shaft 31 which is connected to the shaft 26 by a collar 26' fast on the upper end of the shaft 26, another collar 31' fast on, or forming an enlargement of, the lower end of the shaft 31, and a pin 32 fast in one of these collars but projecting into a hole in the other. An extension 26'', Fig. 5, of the shaft 26 projects into a hole in the collar 31' and centers the two shafts 26 and 31 with each other. With this arrangement, therefore, any rotative movement of the shaft 26 is transmitted accurately to the indicator shaft 31.

Keyed to the shaft 31 is a disk 33, the peripheral surface of which is suitably graduated—in this case in tenths of thousandths of an inch. Part of the periphery of this dial, facing toward the front of the machine, is exposed through a window 34, Figs. 3 and 4.

Immediately above the dial 33 is another dial 35, and the two are connected together through a reduction gearing having a ratio, in this particular case, of ten to one. That is, a pinion 36, Figs. 4 and 5, on the upper end of the dial shaft 31, meshes with, and drives a gear 37 revolving on a stub shaft 38, and another pinion 40 revolving with the gear 37 meshes with a gear 41 which is pressed on to the upper end of a bushing 42 with which the dial 35 also has a pressed fit. The peripheral face of this dial 35 is graduated in thousandths of an inch.

In using this mechanism, and assuming, for instance, that a workman is operating the machine to produce a ground surface of a given diameter on a certain piece of work, and he finds, upon measuring a sample piece, that it is three ten-thousandths of an inch too large, he can make the required change in the position of his grinding wheel merely by pushing the proper button to start up the adjusting mechanism and stopping the motor again when the desired correction has been made. And he can read the degree of adjustment, while so produced, very easily and accurately on the dial 33. In fact, he can even split a ten-thousandth of an inch with this mechanism, and he can do so with little effort because all he has to do is to operate one or two push buttons and read the results on the dial. This arrangement, therefore, enables the operator to make his adjustments of the grinding wheel quickly, easily, and with a degree of accuracy that has never been obtainable heretofore in any machine of this character, so far as we are aware, without a great deal of labor.

While the quill above referred to is highly useful in moving the grinding wheel toward and from the work between fixed limits, the cross-feed is valuable in moving the whole head assembly, both for the purpose of correcting the position of the wheel in its relation to the work, and also in making the initial adjustments required in setting up for a different work piece.

If the over-all movement of the wheel head required in making any adjustment is large, say several inches, the operator can adjust the speed of the motor 22 to its maximum, or thereabouts, until the greater part of the adjusting movement has been produced, and then slow it down to a very low speed while he brings the wheel to exactly the position desired.

The reduction gearing is enclosed in a casing, parts of which are integral with the bracket 21, and it holds ample lubricating material for the gears. This material may be supplied through the oil cup 43, Fig. 2.

Figs. 8, 9 and 10 illustrate a modification of the mechanism for driving the nut 20 which differs primarily from the arrangement above described in that it employs a constant speed electric motor and the mechanism for transmitting motion from this motor to the nut includes a two-speed gearing. Referring first to Fig. 8, the shaft 18, nut 20, and the driving worm 27 for the nut, are the same as in the construction earlier described. The motor 44 is supported vertically on a bracket 21' which takes the place of the bracket 21, shown in Fig. 1. Fast on the shaft 45 of this motor is a worm 46, Fig. 10, driving a worm wheel 47 which revolves freely around the shaft 48. At the right-hand end, Fig. 8, of this shaft it carries a worm 49 driving a worm wheel 50 fast on the lower end of the worm shaft 26, Fig. 8. Consequently, one chain of driving connections between the motor and the worm 27 come through the shaft 48 in this way.

Another chain of driving mechanism includes a spur gear 51, Figs. 8 and 10, fast on the motor shaft and driving a pinion 52 on a vertical shaft 53. A spiral gear 54, Fig. 9, fast on this shaft drives a cooperating gear 55 mounted to revolve around the shaft 48. Consequently, when the latter gear is connected with the shaft 48 to drive it, it also operates through the connections above described to revolve the nut 20.

Between these two gears 47 and 55, mounted to revolve around the shaft 48, is a clutch 56 slideable on said shaft but splined to it, and operable to connect these gears selectively to the shaft. Preferably this clutch is arranged to be operated by a lever 59 fast on the rock shaft 58 and another lever 57 also secured on said rock shaft and pivoted to the plunger of a solenoid 60, Figs. 10 and 11, the solenoid serving to shift the clutch in one direction while the spring 61 moves it in the opposite direction.

With this arrangement, therefore, the motor may be made to drive the wheel head either at high or low speed, as desired. Control of the motor is accomplished through a push button arrangement, as in the construction above described, and by using a reversing switch, the mechanism may be arranged to drive the wheel-head in either direction. For example, if an 1800 R. P. M. motor is used, the connections with the switch controlling it should be so arranged that the solenoid for the high speed gearing will be connected in parallel with the switch and will shift the clutch to bring the high speed gearing into action simultaneously with de-energizing the solenoid. When the slow speed button is pushed, the solenoid then will not be in circuit, and the clutch will be shifted back to its low speed condition by the spring 61. The low speed gearing drive may, in a typical instance, have a ratio of approximately two thousand to one, while the high speed drive may be in the neighborhood of forty to one.

Fig. 12 is a wiring diagram of a control system for use with the driving mechanism just described, the mechanical parts, as well as the wiring, being shown diagrammatically. As there illustrated, the motor 44 is of the three-phase constant speed type equipped with a built-in brake which is automatically released by a solenoid when power is on the motor. It is connected with the power supply lines 62 through two switches or contactors indicated at A and B, respectively. They are arranged to be electromagnetically operated by coils or solenoids C and D, respectively, but springs connected to the plungers of these solenoids normally hold the switches opened. These switches A and B are, in turn, controlled by push buttons, or pull and push switches, indicated at E and F, and these preferably, also, are spring-controlled so that when either switch is not held in its "in" or "out" position it will be returned automatically to a neutral position. In the latter position both coils C and D are de-energized, the switches A and B consequently open, and the motor is de-energized. Preferably, also, these manually operated push buttons or switches E and F are so interlocked, in ways well understood in this art, that it is impossible for both switches A and B to be closed at the same time.

Assuming that the operator wishes to move the grinding wheel 2 toward the work W at a fast rate, he will push the switch F to its "in" position, where the switch cross-bar will connect the contacts a, b and c together. This, as will readily be observed, connects both the coil C and the solenoid 60 across one phase of the supply line. Consequently, the motor is started up and simultaneously the clutch is shifted into the position shown in Fig. 12 where it connects the driving shaft of the motor through the gears 51 and pinion G corresponding, in a general way, to the high speed drive above described, to the shaft H and the gear I fast on it, to the feed screw nut 20. This moves the feed screw 18 and, hence, the entire wheel head assembly inwardly toward the work piece W.

When it is desired to withdraw the wheel head at a high rate of speed, the fast switch F is pulled out, which has the effect of de-energizing the coil C, energizing the opposite coil D, and maintaining the solenoid 60 energized. Thus the direction of rotation of the motor is reversed, due to the fact that the switch A is opened and the switch B is closed. The wheel head will continue to be withdrawn until the fast switch F is moved to its neutral position.

When it is desired to use the slow-motion feed, the switch F remains in neutral and the slow switch E is operated. It will be observed that the contacts of this switch are cross-connected with those of the fast switch so that when it is pushed in, the motor is started up exactly as before. However, there are no connections between the slow switch E and the solenoid 60 so that at this time the spring 61 holds the clutch 56 in engagement with the pinion 46' loose on the motor shaft. This pinion meshes with the large pinion I and thus revolves the feed nut 20 at a very slow speed. In other respects the action of the slow switch E is like that of the fast switch F, the only difference being that the clutch has been shifted so that the low ratio drive of the gears connecting the motor with the feed screw nut 20 drive the latter at a much lower speed.

Thus, with this arrangement, the cross-feed

of the wheel head, in or out, may be produced at either a high or low speed, both these speeds, however, being fixed and predetermined. This is a disadvantage in many cases and it is preferable, therefore, to use a direct current motor because its speed of operation can be controlled by variations in the voltage applied to it. A practical difficulty in accomplishing this result, however, is the fact that direct current is rarely available in a manufacturing plant. Accordingly, in order to make it convenient for a customer to use the machine equipped as shown in Figs. 1 to 6, inclusive, it has been necessary to devise a special control system to satisfy the practical conditions as they exist in almost any machine shop.

Fig. 13 illustrates such a system provided by this invention. As there shown diagrammatically, the motor 22 is connected to the nut 20 and the feed screw shaft 18 in a manner to function as illustrated in Fig. 3. Alternating current supplied by the line 64 is led into a rectifying unit of the electronic type shown at 65. The particular unit there illustrated is that known commercially as the "Thymotrol" rectifier manufactured and sold by the General Electric Company. It delivers direct current to the terminals 66 to 70, inclusive.

The first two of these terminals are connected by conductors to the shunt field 71 of the motor 22, but the speed of this motor is controlled by varying the voltage across the motor brushes, while its direction of rotation is controlled by the reversing switch R—R'. Conductors connect this switch with the motor armature 22', and an interpole field 72 and a series field 73 are connected in series in the armature circuit. While the reversing switch is connected directly to the terminals 69 and 70, the voltage maintained across these terminals is controlled by the variable voltage applied at the terminal 68. This voltage is supplied by either of two potentiometers P and P', connected in parallel across the line fed by the terminals 66 and 67 and they include pivoted contact arms M and M', respectively, so that the position of these arms determines the value of the voltage at the terminal 68 which, as just stated, controls the voltage across the terminals 69 and 70. The application to the motor of either of the voltages so produced at any instant is controlled by two push and pull switches 74 and 75, respectively, operating in conjunction with the reversing switch R—R'.

Assuming, for example, that there is a constant voltage of 240 across the terminals 66 and 67, the voltage of the former being zero, and that the arms M and M' are so adjusted that the voltage delivered at the pivotal point of the arm M is 40, while that at the corresponding point of the arm M' is 200, these two control voltages may be conducted selectively to the Thymotrol terminal 68 by the operation of the slow or fast switch 74 or 75, as desired.

Assuming that the operator desires to move the wheel head 3 toward the work W at a slow speed, he pushes the slow speed push switch or button 74 in so that its upper cross-bar completes a circuit from the switch arm M to the Thymotrol terminal 68. At the same time the lower cross-bar of the switch 74 closes a circuit through the actuating solenoid 76, thus closing the section R of the reversing switch. This starts the motor 22 in operation at a rate of speed determined by the low voltage of 40 delivered across the terminals 69 and 70. Assuming that the motor 22 is built for a normal voltage of 240, the speed necessarily

will be slow, but because the motor is compound-wound, its torque will be ample to perform the duty required of it, with the result that it will operate through the reduction gearing shown in Fig. 3 to move the wheel head inwardly at a very slow rate.

Both the switches 74 and 75 preferably are spring-controlled, as above explained in connection with the switches E and F, so that they return to their neutral or open positions as soon as released. Consequently, when the switch 74 is released, the motor stops and the grinding wheel remains in the position to which it has been adjusted, the opening of the switch 74 also de-energizing the coil 76 of the reverse switch and causing it to return to its normally open position, as in the system previously described.

If, now, the slow switch 74 is pulled out, it will close a circuit through the coil 77 for the reversing switch, thus causing the section R' of this switch to close and reversing the direction of rotation of the motor 22 but at a slow rate of speed.

To operate the wheel head at a high speed, the fast switch 75 is pushed in or out, depending upon the desired direction of rotation, whereupon the same functions are performed as above described in connection with the switch 74, except that an operating voltage of 200 is now applied to the motor through the potentiometer P', and the motor runs at a correspondingly higher speed.

Either the slow or the fast speed of the motor may be adjusted up or down from the values above assumed by moving the potentiometer arms M or M', and in this way a wide variation in the rate of movement of the wheel head toward or from the work may be produced at any time. This extraordinary flexibility is very valuable in a machine shop handling a great variety of work, and it is obtainable with the construction shown by apparatus which is very reliable, relatively simple, and not liable to get out of order. For these reasons this direct current drive is much preferred to the alternating current system above described.

The motor 22 when driven by a "Thymotrol" unit provides a regenerative braking. That is, when the current is cut off, the momentum tends to keep the motor running, but the rotation of the armature then changes the motor into a generator which quickly brings it to a stop. No other type of brake is necessary with this arrangement.

The switches for controlling the operation of either motor preferably are mounted on a switch panel which also contains switches, levers, or other elements for controlling other functions of the machine. A portion of such a panel is illustrated at 30 in Fig. 14, and the knobs or handles of the switches 74 and 75 are there shown, in their normal positions, on the panel. Also mounted on this panel, but preferably not so readily accessible, are the adjustable arms for the potentiometers P and P', and all of the controls are located in some position such that the operator can reach them all easily, although such positions may be relatively remote from the respective motors or other instrumentalities which they control. In particular, the panel should be so positioned that the operator can readily see the indicator dials while he manipulates the control switches.

The means above referred to for supporting the work for the grinding operation may be of any suitable character. A typical arrangement is illustrated in Fig. 15 where the revolving centering devices 78—78 carried by the respective shafts

6—6 are mounted for relative movement toward and from each other to release the work piece while another is placed in position to be operated upon. These operations usually are performed automatically.

In this connection it should be pointed out that the power for driving the indicator is taken from the reduction gearing at the point of lowest speed of this mechanism, namely, the shaft 26. Consequently, any error due to back-lash is substantially eliminated. Moreover, because no work is required of this shaft 26, except to move the indicator dials, it is free from torsional deflection and the indication of measurement, therefore, is exceptionally accurate. In the mechanisms above described the relative approaching and receding movements of the grinding wheel and the work are produced by movements of the wheel or the wheel-head. It is obvious, however, that this same result might be produced by moving the work holder. Also, that in producing these movements of the wheel-head either the nut 28 or the screw 18 can be revolved while the other member remains stationary. It has here been considered more convenient to revolve the nut. Both of the modifications just described are equivalents of the constructions shown and that the claims are intended to be interpreted accordingly.

While we have herein shown and described preferred embodiments of our invention, it will be evident that the invention is susceptible of embodiment in other forms without departing from the spirit or scope thereof.

Having thus described our invention, what we desire to claim as new is:

1. A grinding machine including a work holding device, a grinding wheel, a wheel head in which said wheel is mounted for rotation, and means supporting said wheel head and the work holding device for relative approaching and receding movements; mechanism for producing said movements comprising a screw-threaded shaft, a nut threaded on said shaft, said nut and said shaft being so associated with said wheel head and with said supporting means that rotation of the nut moves the wheel head toward and from the work, a motor, a speed reduction mechanism through which power is transmitted from said motor to said nut to revolve it, and an indicator driven by said speed reduction mechanism and constantly showing measurements of said relative approaching and receding movements.

2. In a grinding machine according to preceding claim 1, a construction in which said nut is in the form of a worm wheel, and said speed reducing mechanism includes a worm meshing with said nut to revolve it.

3. In a grinding machine according to preceding claim 1, a construction in which said indicator is mounted on and moves with, the wheel head, and said screw-threaded shaft connects said wheel head with said supporting means on which the wheel head is mounted.

4. In a grinding machine according to preceding claim 1, a construction in which said indicating mechanism is driven by the element of said speed reduction mechanism which engages and revolves said nut.

5. In a grinding machine according to preceding claim 1, a construction in which said speed-reducing mechanism comprises a worm located substantially at the slow speed end of the speed reduction mechanism, and the driving element for said indicator is connected with said worm to be revolved in unison with it.

6. In a grinding machine including a grinding wheel, a wheel head in which said wheel is mounted for rotation, devices for supporting the work for the operation thereon of said grinding wheel, and means supporting said wheel head and said work supporting devices for relative approaching and receding movements; mechanism for producing said movements comprising a screw-threaded shaft, a nut threaded on said shaft, said nut and said shaft being so associated with said wheel head and with said supporting means that rotation of the nut moves the wheel head toward and from the work, a drive shaft, a speed reduction mechanism connecting said drive shaft with said nut to revolve the latter, and an indicator driven from the low speed end of said speed reduction mechanism and calibrated to show constantly measurements of said relative approaching and receding movements.

7. In a grinding machine according to preceding claim 6, a construction in which said indicator is mounted on the wheel head for movement toward and from the work with said head, and comprises a large dial positioned at a considerable elevation above the body portion of the wheel head.

8. In a grinding machine according to preceding claim 6, a construction in which said indicator comprises a vertical shaft connected with the lowest speed shaft of said speed reduction mechanism to be driven by the latter, a graduated dial on the upper end of said shaft, and a casing substantially enclosing said shaft and said dial.

9. In a grinding machine according to preceding claim 6, a construction in which said indicator comprises a vertical shaft connected with the lowest speed shaft of said speed reduction mechanism to be driven by the latter shaft, a graduated dial on the upper end of said shaft, a second graduated dial mounted to revolve around the axis of said shaft, gear connections between said shaft and the second dial for driving the latter in a predetermined speed ratio to the former, and a casing substantially enclosing said indicating mechanism.

10. In a grinding machine according to preceding claim 1, a construction in which said motor is of the variable speed reversible direct current type, whereby the variation in the rate of adjustment of the said relative approaching and receding movements can be produced by adjustment of the motor speed.

11. In a grinding machine according to preceding claim 1, a construction in which said motor is of the variable speed direct current type, whereby the adjustment of speed of the nut is obtainable directly by adjustment of the motor speed, and controlling apparatus for said motor, positioned remotely from it, but so connected with it and so organized as to control the starting, stopping, reversing and the change of speed of the motor.

12. In a grinding machine according to preceding claim 1, a construction in which said speed reduction mechanism includes a changeable speed gearing.

13. In a grinding machine including a grinding wheel, a wheel head in which said wheel is mounted for rotation, and means supporting said wheel head and the work for relative approaching and receding movements; mechanism for producing said movements comprising a screw-threaded shaft, a nut threaded on said shaft, said nut and said shaft being so associated with said wheel head and with said supporting means that

rotation of the nut moves the wheel head toward and from the work, a motor, mechanism through which power is transmitted from said motor to said nut to revolve it, and an indicator driven by the latter mechanism and constantly showing measurements of said relative approaching and receding movements.

14. In a grinding machine according to preceding claim 6, a construction in which said indicator comprises a vertical shaft connected with the lowest speed shaft of said speed reduction mechanism to be driven by the latter, and a graduated dial mounted on the upper end of said vertical shaft and driven by said lowest speed shaft.

15. In a grinding machine including a grinding wheel, a wheel head in which said wheel is mounted for rotation, means supporting said wheel head and the work for relative approaching and receding movements; mechanism for producing said movements comprising a screw-threaded shaft, a nut threaded on said shaft, said nut and said shaft being so associated with said wheel head and with said supporting means that rotation of the nut moves the wheel head toward and from the work, a variable speed reversible electric motor, mechanism through which power is transmitted from said motor to said nut to revolve it, and control apparatus for said motor comprising switches operable to start, stop and reverse it, the motor being equipped with an automatic brake for stopping it instantly when the power supply to it is cut off, and said controlling apparatus including an electronic rectifier system and means operatively connected with it and adjustable to vary the voltage impressed on said motor so that the speed of relative approaching and receding movements of the wheel head may be adjusted by varying said voltage.

16. A grinding machine of the class described, including a work holding device, a wheel head, a grinding wheel mounted for rotation in the wheel head, said grinding wheel being adjustable in the wheel head toward and away from the work holding device, means supporting said wheel head and the work holding device for relative approaching and receding movements, in combination with mechanism for producing said approaching and receding movements independently of adjustment of the grinding wheel in the wheel head, said mechanism comprising a screw-threaded shaft, a nut threaded on said shaft, said nut and said shaft being so associated with said wheel head and with said work holding device that rotation

of the nut moves the wheel head toward and from the work, a motor, a speed reduction mechanism through which power is transmitted from said motor to said nut to revolve it, and an indicator driven by said speed reduction mechanism and constantly showing measurement of said approaching and receding movements.

17. In a grinding machine including a grinding wheel, a wheel head in which said wheel is mounted for rotation, and means supporting said wheel head and the work for relative approaching and receding movements; mechanism for producing said movements comprising a screw-threaded shaft, a nut threaded on said shaft, said nut and said shaft being so associated with said wheel head and with said supporting means that rotation of the nut moves the wheel head toward and from the work, a motor, mechanism through which power is transmitted from said motor to said nut to revolve it, apparatus remote from said motor but connected with it and organized to control the operation of said motor, said motor being of the constant speed type and said power transmitting mechanism including changeable speed gearing comprising a clutch operable to shift from one speed to another, switches remote from said motor but connected with it to control its operation, and electromagnetic means for operating said clutch connected with one of said switches to be operated thereby.

HARRY ARTER.
